UNITED STATES PATENT OFFICE

101,466

DESIGN FOR A SERVICE STATION

Leonard D. Long, Charleston, S. C.

Application May 18, 1936, Serial No. 62,712

Term of patent 14 years

To all whom it may concern:

Be it known that I, Leonard D. Long, a citizen of the United States, residing at Charleston, in the county of Charleston and State of South Carolina, have invented a new, original, and ornamental Design for a Service Station, of which the following is a specification, reference being had to the accompanying drawing, forming part thereof.

Figure 1 is a view in front elevation of a service station, showing my new design.

Figure 2 is a view in top plan thereof. The back of the building is substantially the same in appearance as the front. The drawing is shaded to show contrasting colors.

I claim:

The ornamental design for a service station as shown and described.

LEONARD D. LONG.
